(57) **CLAIM**

The ornamental design for a candle jar with lid, as shown and described.

DESCRIPTION

FIG. 1 is a perspective view of candle jar with lid, showing our new design;

FIG. 2 is an exploded front view thereof;

FIG. 3 is a front view thereof;

FIG. 4 is a left view thereof;

FIG. 5 is a right view thereof;

FIG. 6 is a back view thereof;

FIG. 7 is a top view thereof; and,

FIG. 8 is a bottom view thereof.

The subject matter shown in dashed lines is for environmental purposes and forms no part of the claimed design.

1 Claim, 8 Drawing Sheets
